ULTRA HIGH FREQUENCY APPARATUS

Martin R. Richmond, Brooklyn, N. Y., assignor to
Radio Corporation of America, a corporation
of Delaware

Application February 25, 1943, Serial No. 477,167

9 Claims. (Cl. 250—13)

1

This invention relates generally to ultra-high frequency apparatus and more particularly to duplex switching apparatus for controlling simultaneously separate power and signal circuits applied to different components of a communication system.

In ultra-high frequency communication systems it is often desirable to control simultaneously the application of potentials derived from a power source to a signal generator and to isolate selectively a receiver from a signal source. Due to the peculiarities inherent in ultra-high frequency apparatus, conventional switching means are seldom entirely satisfactory due to undesired reactive components which are thus introduced into the associated circuits. The instant invention contemplates the use of a current discharge device which may be keyed to provide a conductive path for connecting the power source to the signal generator while simultaneously presenting an open circuit to the signal path between the received signal source and the signal receiver. Various modifications of the invention will be described in detail hereinafter. However, all involve the common feature of providing simultaneous control of a current discharge path and a wave transmission path, such as, for example, a wave guide or a resonant chamber. This feature permits higher power control since it substantially eliminates the power surge, or "spike" introduced into the wave transmission path when the wave path alone is keyed. Other modifications of the invention are disclosed and claimed in applicant's copending application Serial No. 508,332, filed October 30, 1943, as a division of the instant application.

Among the objects of the invention are to provide a new and improved method of and means for providing simultaneous switching of a power source and a wave transmission path. Another object of the invention is to provide an improved method of and means for providing a duplex ultra-high frequency switching device which comprises a current discharge path for a power source and a wave attenuator for a signal source. Another object of the invention is to provide an improved method of and means for controlling simultaneously the conductivity of a power transmission circuit and the attenuation of an ultra-high frequency wave transmission circuit. Still another object of the invention is to provide an improved method of and means for controlling simultaneously a power circuit and a wave transmission circuit through a dielectric wave guide.

Still another object of the invention is to provide an improved method of and means for con-

2

trolling a power circuit and an ultra-high frequency wave transmission circuit through a resonant chamber by providing a current discharge within said chamber to vary the impedance thereof at the operating frequency.

The invention will be described in greater detail by reference to the accompanying drawing of which Figure 1 is a block diagram of one embodiment of the invention; Figure 2 is a cross-sectional view of an embodiment of the invention; Figure 3 is a cross-sectional view along the line AA of Figure 2; and Figure 4 is a cross-sectional view of a modification of the invention. Similar reference numerals are applied to similar elements throughout the drawing.

Referring to Figure 1, a transmitter 1 is supplied with operating potential from a transmitter power source 2 through a duplex switching device 3 of any of the types to be described in detail hereinafter. An antenna, or other signal source, 4 is connected to the input of a wave transmission circuit 5 such as, for example, a wave guide or a coaxial transmission line. The wave transmission circuit 5 also is connected through the duplex switching device 3 to a signal responsive device such as a radio receiver 6. A source of keying pulses 7 is connected to the duplex switching device 3. When a keying pulse from the keying source 7 is applied to the duplex switch 3, the power circuit from the power source 2 is completed through the switch 3 to the transmitter 1. Simultaneously, the wave transmission circuit 5 is effectively interrupted to isolate the receiver 6 from the signal source 4. During the intervals between keying pulses from the keyer circuit 7, the power circuit from the transmitter power source 2 to the transmitter 1 is interrupted at the switch 3, while the wave transmission circuit through the transmission line 5 is completed from the signal source 4 to the signal receiver 6.

Figure 2 includes a section of wave guide 5 having a projection 6 extending transversely across a portion of the wave path. The wave guide is entirely enclosed within an evacuated envelope 10. Opposite the projection 6 is a second projection 8 comprising a cathode surface which is heated by a heater winding 9. A grid element 11 is disposed in the aperture formed in the guide between the cathode 8 and the projection 6. Separate leads are brought out through seals for the cathode, heater, grid and wave guide elements.

It should be understood that the device just described constitutes a thermionic discharge tube in which the projection 6 represents the anode of the tube. The shape of the aperture formed

between the cathode and the anode elements of the discharge tube may be more clearly seen from the end view shown in Figure 3. The aperture thus formed constitutes a resonant aperture of the type described in detail in the copending application of William D. Hershberger, Ser. No. 477,176 filed February 25, 1943. Capacitive elements 12, 13 are disposed adjacent the supports of the grid 11, to bypass effectively the ultra-high frequency current components induced therein. 10

In operation, if the grid electrode 11 is biased negatively with respect to the cathode 8, and the anode 6 is positive with respect to the potential on the cathode 8, substantially no electron discharge will occur across the gap formed between the cathode and anode. Since the aperture is resonant at the wave transmission frequency, it provides an efficient transfer path through the wave guide 5 for waves introduced into the wave guide. However, if a positive potential is applied to the grid electrode 11, such as keying pulses from the keyer circuit 1, a current discharge path occurs across the gap between the cathode 8 and the anode 6 which effectively changes the resonant characteristics of the resonant aperture formed thereby. This change in resonance effectively blocks wave transmission through the wave guide, while it also provides a conductive path from the cathode 8 to the anode 6 which may be utilized for the transmission of power from the power source 2 to the transmitter 4.

It should be understood that the envelope 10 may be evacuated to form a vacuum type thermionic tube within the wave guide, or it may be filled with an inert gas at low pressure to provide a tube of the Thyratron type of gaseous discharge tube. If the tube just described is of the vacuum type, effective keying of any type of transmitter power source may be accomplished by the means of positive keying pulses derived from the keyer circuit 1, providing a normal negative bias is applied to the grid 11. However, if the tube thus formed is of the Thyratron type, the circuit may only be keyed "on" by the positive keying pulses, and interruption of the discharge path must be accomplished by reducing the positive potential applied to the anode 6. Such a condition will prevail if the transmitter power source provides alternating potentials or pulsating potentials of varying voltage between some predetermined maximum and zero value. Preferably, the ends of the wave guide 5 should extend as closely as possible to the envelope 10 in order that the device may be coupled efficiently to external transmission circuits.

Figure 4 is similar to the device described in Figures 2 and 3 with the exception that apertured conductive elements 31 and 32 extend transversely across the wave guide 5 to form a resonant cavity 40 which includes the current discharge device consisting of the anode 6, the grid 11, and the cathode 8. Capacitive elements 12 and 13 may also be employed to bypass ultra-high frequency currents induced in the grid electrode 11. A current discharge occurring within the resonant cavity 40 will change the resonant characteristics thereof to provide a circuit of extremely high impedance to waves of the signal frequency. The size of the apertures in the apertured elements 31, 32 may be selected to provide the desired selectivity in the tuning of the resonant cavity 40, as described in the copending application mentioned heretofore.

In all of the devices described heretofore, it

should be understood that the wave transmission path is through the particular wave transmission device described, while the power transmission path is between the cathode and anode or current discharge electrodes. It should also be understood that in each of the modifications described, the occurrence of a current discharge, whether electronic or ionic, will provide a conducting path which will complete the circuit between the power source and the transmitter, while simultaneously effectively blocking the transmission of signal waves through the device from the signal source to the signal receiver.

Thus the invention described comprises new and improved methods of and means for switching simultaneously a power circuit and a wave transmission circuit in response to pulses derived from a keying source.

I claim as my invention:

1. In a system of the type including a signal generator, a signal responsive device, a source of operating potential for said signal generator, and a signal source for said signal responsive device, the improvement comprising a duplex current discharge switching device comprising means providing a wave transmission path for coupling said signal source to said signal responsive device and means for selectively providing a current discharge transversely of said wave transmission path, and means for initiating a current discharge within said device for applying said operating potential to said signal generator and effectively isolating said signal responsive device from said signal source, and for alternately quenching said current discharge thus effectively isolating said signal generator from said potential source and effectively coupling said signal responsive device to said signal source.

2. In a system of the type including a radio transmitter, a radio receiver, a source of operating potential for said transmitter, and a signal source for said receiver, the improvement comprising a duplex current discharge switching device comprising means providing a wave transmission path for coupling said signal source to said receiver and means for selectively providing a current discharge transversely of said wave transmission path, and means for initiating a current discharge within said device for applying said operating potential to said transmitter and effectively isolating said receiver from said signal source, and for alternately quenching said current discharge thus effectively isolating said transmitter from said potential source and effectively coupling said receiver to said signal source.

3. In a system of the type including a radio transmitter, a radio receiver, a source of operating potential for said transmitter, and a signal source for said receiver, the improvement comprising a duplex electron discharge switching device comprising means providing a signal wave transmission path for coupling said signal source to said receiver and means for selectively forming a current discharge path transversely across said signal wave transmission path to effectively block said signal transmission, and means for initiating a current discharge in said device for applying said operating potential to said transmitter and effectively isolating said receiver from said signal source, and alternately for quenching said current discharge in said device thus effectively isolating said transmitter from said potential source and effectively coupling said receiver to said signal source.

4. In a system of the type including a signal

generator, a signal responsive device, a source of operating potential for said signal generator, and a signal source for said signal responsive device, the improvement comprising a duplex current discharge device comprising a resonant chamber for coupling said signal source to said signal responsive device, and means for selectively forming a current discharge within said resonant chamber to vary the resonant frequency of said chamber, and means for initiating said current discharge within said device for applying said operating potential to said signal generator and effectively isolating said signal responsive device from said signal source, and alternately for quenching said current discharge thus effectively isolating said signal generator from said potential source and effectively coupling said signal responsive device to said signal source.

5. In a duplex current discharge switching device in combination with a signal generator, a signal responsive device, a source of operating potential for said signal generator and a signal source for said signal responsive device, the method comprising establishing a current discharge within said device, utilizing said current discharge for applying said operating potential to said signal generator and effectively isolating said signal responsive device from said signal source, and alternately quenching said current discharge thus effectively isolating said signal generator from said potential source and effectively coupling said signal responsive device to said signal source.

6. In a duplex current discharge switching device in combination with a signal generator, a signal responsive device, a source of operating potential for said signal generator and a signal source for said signal responsive device, the method comprising keying said device for establishing a current discharge within said device, utilizing said current discharge for applying said operating potential to said signal generator and effectively isolating said signal responsive device from said signal source, and alternately quenching said current discharge thus effectively isolating said signal generator from said potential source and effectively coupling said signal responsive device to said signal source.

7. A duplex current discharge switching device for use with a power circuit and a signal responsive device, said switching device comprising means providing a wave transmission path for signals to said signal responsive device, means

providing a series current path transversely of said wave transmission path in said switching device for said power circuit, and means for initiating a current discharge in said switching device for completing said series path and effectively interrupting said signal transmission path for isolating said signals from said signal responsive device, and for alternately quenching said current discharge for interrupting said series path and effectively completing said signal transmission path.

8. A duplex current discharge switching device for use with a signal generator, a source of operating potential for said generator, a signal source and a signal responsive device responsive to said signal source, said switching device comprising means providing a signal wave transmission path for signals from said signal source to said signal responsive device, means providing a series path transversely of said wave transmission path in said switching device for operating potentials from said potential source to said generator, and means for initiating a current discharge in said switching device for applying said operating potential to said generator and effectively interrupting said signal wave transmission path thereby isolating said signal source from said signal responsive device, and for alternately quenching said current discharge for removing said operating potential from said generator and effectively completing said signal transmission path.

9. A duplex current discharge switching device for use with a power circuit and a signal responsive device, said switching device comprising waveguide means providing a wave transmission path for signals to said signal responsive device, means comprising an electron discharge device disposed within said waveguide and providing a series path transversely of said wave transmission path through said switching device for said power circuit, and keying means operable upon said electron discharge device for initiating a current discharge in said switching device for completing said series path and effectively interrupting said signal wave transmission path for isolating said signals from said signal responsive device, and for alternately quenching said current discharge for interrupting said series path and effectively completing said signal transmission path.
